UNITED STATES PATENT OFFICE.

ATKINS STOVER, OF BROOKLYN, NEW YORK.

METAL-SHEARING MACHINE.

SPECIFICATION forming part of Letters Patent No. 329,096, dated October 27, 1885.

Application filed May 25, 1885. Serial No. 166,576. (No model.)

To all whom it may concern:

Be it known that I, ATKINS STOVER, of Brooklyn, in the county of Kings and State of New York, have invented an Improvement 5 in Shears for Metal, of which the following is a specification.

Shears for metal have been made with a base-block and head-block in one piece, and a bed-shear bolted upon the base-block and 10 the swinging shear pivoted to the head-block, the swinging shear moving against a flat face upon the head-block. In this form of shear there is considerable friction of the swinging shear against the head-block, and the movement of the same is interfered with, and the 15 shear injured by any particles of metal passing in between the swinging shear and the head-block.

My improvements are made for removing 20 the aforesaid risk of injury and for rendering the cutting-action of the shear more uniform, so that the leverage will be as great in finishing the cut as in commencing it, and I provide a movable gage against which the material to be cut is stopped, as it is passed through, 25 from time to time.

In the drawings, Figure 1 is a side view of the shear. Fig. 2 is an end view of the same. Fig. 3 represents the face of the head-block 30 with the shear-lever and links removed, and Fig. 4 is a section at the line $x-x$, Fig. 1.

The base-block A and head-block B are cast together with an opening at the place where the shears are applied to admit the insertion 35 of the article to be cut. Upon the base-block A are feet or lugs a , by which the shear is bolted to a suitable support. The shear C is received into a recess in the side of the base-block A, this recess being made with vertical 40 ribs for the shear to rest against. These ribs are easily planed off perfectly true and level for the reception of the shear, and the bolts d are made use of for attaching the shear to the base-block. The swinging shear D is connected to the head-block B by a pivot-bolt, 45 E, which bolt passes through a hub cast upon the head-block. The head-block itself is made with a stiffening-rib along its upper portion, and its vertical surface is recessed for the reception of the swinging shear, and there are vertical ribs i projecting from the surface of 50 the head-block, against which the side of the

swinging shear D moves. These ribs i lessen the friction of the shear against the side of the head-block, and in case of any particles of metal passing in between the swinging shear and the side of the head-block the shear is not displaced by the same, as such foreign substances slip off the ribs i into the intermediate recesses. At the end of the head-block B is a 55 joint, H, for the reception of the end of the lever K. This lever is made with a downward projection, k , to which are attached links l by the cross-bolt o . These links pass down at opposite sides of the projecting end of the 60 swinging shear D, and are connected thereto by the pivot-bolt n . When the lever K is raised the pivot-bolt o , swinging in the arc of a circle, assumes a position nearly level with the bolt of the joint H. The shear being wide 65 open at this time, the material to be cut is slipped in almost to the pivot-bolt E; hence, when the lever K is pressed down, the material is cut freely by the leverage of the shear upon such material. As the cutting 70 progresses the point of separation is moved away from the pivot-bolt E, lessening the leverage of the shear against the material being cut, but at the same time the bolt o , swinging in the arc of a circle down beneath the joint H, 75 80 the links l and lever act jointly, like toggle-bars, to increase the power of the lever K in cutting off the material acted upon, thus equalizing to a great extent the power necessarily exerted in shearing sheet metal or other 85 material.

In the base-block A is a transverse mortise for the reception of the stock P of the gage Q, and there is a clamping-screw, r , for holding the stock of the gage in any position to which 90 it might be adjusted. This gage can be set at any desired position for stopping the end of the sheet, rod, or other article that is to be cut up.

I do not claim a gage, or a gage applied to 95 cutting-shears, as these are old and well-known.

I claim as my invention—

1. The base-block A and head-block B, cast in one piece and having recesses, and ribs i at 100 the bottom of the recesses, in combination with the bed-shear C in the recesses in the base-block and bolted against the ribs thereof, the swinging shear D in the recess of the head-

block and resting against the ribs *i*, the pivot-bolt *E*, passing through the shear and through a hub on the head-block, the joint *H*, lever *K*, links *l*, and bolts *n o*, substantially as set forth.

2. The combination, with the swinging shear *D* and bed-shear *C*, of the head-block *B*, recessed and provided with ribs for supporting the swinging shear *D*, the base-block *A*, integral with the head-block *B* and having

a mortise through it, the stock *P*, passing through the said mortise, the gage *Q* upon the stock, and the clamping-screw *r*, substantially as set forth.

Signed by me this 20th day of May, A. D. 1885.

ATKINS STOVER.
